UNITED STATES PATENT OFFICE

120,748

DESIGN FOR A TEXTILE FABRIC

Hugh J. Carragher and Thurston B. Wilson,
Brooklyn, Conn., assignors to Powdrell &
Alexander, Inc., Danielson, Conn., a corporation of Connecticut

Application April 18, 1940, Serial No. 91,762

Term of patent 3½ years

To all whom it may concern:

Be it known that we, Hugh J. Carragher and Thurston B. Wilson, citizens of the United States, residing at Brooklyn, in the county of Windham and State of Connecticut, have invented a new, original, and ornamental Design for a Textile Fabric, of which the following is a specification, reference being had to the accompanying drawing, forming part thereof.

The figure is a plan view of a textile fabric, showing our new design.

We claim:

The ornamental design for a textile fabric, as shown.

HUGH J. CARRAGHER.
THURSTON B. WILSON.
